US0D1103829S

(12) **United States Design Patent** (10) **Patent No.:** **US D1,103,829 S**
(45) **Date of Patent:** **** Dec. 2, 2025**

(54) **JEWELRY ARTICLE SUCH AS A RING**

(71) Applicant: **Eliantte Group Inc.**, New York, NY (US)

(72) Inventor: **Elliot Buryev**, New York, NY (US)

(73) Assignee: **Eliantte Group Inc.**, New York, NY (US)

(**) Term: **15 Years**

(21) Appl. No.: **29/902,891**

(22) Filed: **Sep. 18, 2023**

(51) **LOC (15) Cl.** **11-01**

(52) **U.S. Cl.**

USPC **D11/34**

(58) **Field of Classification Search**
